COLLAR PRESSING MACHINE

Walter J. Beattie, Cohoes, N. Y., assignor to The Beattie Manufacturing Company, Cohoes, N. Y., a corporation of New York

Application March 12, 1934, Serial No. 715,244

16 Claims. (Cl. 68—9)

This invention relates to ironing or pressing machines, especially designed for ironing collars, and other similar articles. The machine is particularly adapted for use in the home by the housewife or laundress, although it will also find wide utility in commercial laundries.

When men's collars are laundered in the home, it is practically impossible to give them the same finished appearance that the collars originally had when they left the manufacturing plant. This difficulty may be explained largely because of the fact that collars are always ironed in the home on a flat ironing board, and it is, therefore, impossible to impart the desired tapered form to the article. When collars are originally made and finished by the manufacturer, they usually have a slight downwardly and outwardly flaring taper, corresponding generally to the taper of the neck of the wearer, and it is this tapered finish that gives a new collar a distinctive and attractive appearance. However, as soon as the collars are washed and ironed flat, they lose this desirable feature of appearance. The problem arises in finishing both collars of the detached and attached types, because flat ironing of any tapered article necessarily results in puckering or wrinkling of portions of the article.

The principal object of this invention is to provide an ironing appliance which overcomes the above difficulties of present day conventional practice. Primarily, it is an object of the invention to provide a device which will impart to collars the desired tapering form.

It is a further object of the invention to provide an ironing machine which is adapted to iron collars of all of the standard different sizes.

It is a further object of the invention to provide a machine of the class described which is inexpensive, simple, of a relatively small size, and not likely to get out of order.

In the accompanying drawings, a specific embodiment of a machine constructed in accordance with the present invention is disclosed, but it must be understood that the drawings are illustrative only, and that the invention is not limited to the details thereof.

In the accompanying drawings:

Figure 1 is a vertical sectional view of the machine.

Figure 2 is a front elevational view.

Figure 3 is a horizontal sectional view taken substantially on line 3—3 of Figure 2.

Figure 4 is an elevational view of a special ironing tool adapted for use with the machine of the invention, and

Figure 5 is a vertical sectional view of the tool of Figure 4.

The machine of the present invention consists essentially of a heated form adapted to support a collar, in combination with an ironing appliance associated with the form and mounted in such manner that an ironing pad may be moved over the surface of the form to smooth and iron a collar positioned thereon. In the drawings, a substantially frusto-conical tapering form 10 is shown supported upon a base 11. Associated with the base is a clamp 12 comprising a downwardly facing surface 13 adapted to be placed upon a bench or table, and a threaded clamping bolt 14. By this or any equivalent means the form may be clamped in any convenient position in the laundry, and readily removed when not in use. Although the collar supporting form 10 may be heated by any appropriate medium, an electrical heating unit is preferred. In the drawings, such a unit is shown at 15, and the same may be supported by an appropriate mounting 16 on the upper surface of the base plate 11. An electrical conduit 17 extends outwardly through an appropriate hole in the plate 11, and the same may be connected to any suitable source of electrical energy.

The collar supporting form is of tapering shape, so that collars of different sizes may be supported thereon at different positions or levels, in snug fit. Preferably, the exterior surface of the form is provided with a longitudinally extending groove or recess 18 which is adapted to receive the collar button of a collar supported on the form, so that the button will not interfere with the ironing appliance, and, furthermore, so that the button will not leave an objectionable mark upon the finished collar.

The upper end of the form preferably is provided with an inwardly projecting hollow boss 19, and the central bore 20 thereof is machined to cylindrical shape, to act as a bearing surface for a pivot stud associated with the ironing appliance, now to be described.

The device associated with the collar supporting form and adapted to smooth and iron the exterior surface of the collar may conveniently take the form of the device disclosed in the drawings, although many modifications will readily occur to one skilled in the art. This appliance includes a pivot stud 21 removably and rotatably mounted in the bore 20 of the boss, and having an enlarged head 21' provided with a horizontal bore 22. A laterally projecting arm 23 is pivotally connected to the head of the stud by a suitable

pin 24. This arm has an appropriate clamping device at its outer end, and the same is adapted to adjustably hold a depending bar 25. Although any appropriate type of clamp may be used, one of the cam type has been found to be satisfactory. In the drawings, a cam member 26 is mounted on a pin 27 disposed near the outer end of the arm 23. This cam is provided with a rearwardly extending operating handle 28. Thus, by raising and lowering the handle 28, the cam 26 may be rotated, so that the outer surface thereof moves toward or away from the bar 25 to clamp or to release the same.

The bar 25 carries, at its lower end, an ironing tool indicated generally at 29, which may or may not be electrically heated. The tool comprises an ironing pad 30, a spacing block 31 and an operating handle 32. The inner face of the ironing pad is concave on a horizontal section, but is substantially straight on a vertical section. The curve of concavity of the surface of the pad should not be any sharper than the convex curve of the outer surface of the tapering form at its larger end, because if it were, the end portions only of the ironing pad would come in contact with a collar of large size, and an efficient ironing operation would be difficult. As an alternative, the pad may be of spring-like, flexible metal to permit the concave face of the pad to bend or flex and conform to the surface of the conical form, on all different arcs thereof.

The vertical dimension of the ironing pad 30 should be sufficiently long to permit the pad to cover an entire section of a collar from its upper edge to its lower edge. In other words, the height of the pad should be equal to or greater than the height of average collars at the points, so that the vertical position of the pad need not be changed during an ironing operation on any particular collar.

In the use of the apparatus of the present invention, a freshly laundered, damp collar is applied to the form, either by wrapping it around the upper small end, buttoning it, and then sliding it downwardly, or by applying the buttoned collar over the top of the form after the ironing attachment has been removed by withdrawing the stud 21 from the socket 20. In any event, the collar is moved toward the larger end of the form until a snug fit is secured. By working the collar on the form, small wrinkles and the like may be eliminated, and the interior ply of the collar is thus heated, dried and smoothed. The ironing appliance is then placed in position and the handle 28 of the clamp moved so that the pad 30 may be adjusted to overlie the collar. The clamp is then tightened, and the ironing attachment is ready for use. Because of the pivotal mounting, an operator may grasp the handle 32 and move the ironing pad around the surface of the collar on a horizontal path, to smooth, iron and polish the exterior surface of the collar. Since the path of movement of the ironing pad is relatively fixed, the ironing operation may be performed very rapidly, and uniformly successful results will always be accomplished. Thus, both the inner and outer surface of the collar are ironed, and the correct tapered shape is applied to the collar.

The device is equally useful for ironing both collars which are permanently attached to shirts and for collars which are detachable.

As stated above, the ironing pad may be electrically heated, and if such a construction is desired, a heating element 33 may be secured there-

in. The wires for the heating element may be threaded upwardly through an appropriate conduit in the vertical bar 25, or disposed in any other convenient manner.

A modified form of ironing tool is shown in Figures 4 and 5, and this tool may be used in association with the vertical bar 25 and the other parts, or it may be merely held in the hand of the operator and moved over the surface of a collar. In any event, it cooperates with the form to iron the exterior surface of the collar and give a predetermined, desired rounded surface to the upper edge of the collar. Referring to Figures 4 and 5, it will be seen that the tool 35 is concave on a horizontal plane in a manner similar to the pad 30. Adjacent the upper edge of the tool, as shown in Figure 5, there is a relatively sharply rounded concave surface 36 which is adapted to be placed over the upper edge of the collar to give the folded edge the proper rounded and polished surface.

Many modifications of the device shown in the drawings will readily occur to one skilled in the art. For instance, the ironing appliance may be pivoted about the axis of the form at the lower end thereof, so that it will not be necessary to remove the attachment when collars are slipped on and off of the form over the small end. Such a construction presents certain advantages, but is disadvantageous for the reason that the necessary movement of the parts may be hindered by the body of a shirt hanging downwardly from the form.

The necessity for a vertically adjustable mounting for the pad 30 can be dispensed with by making the vertical dimension of the pad sufficiently long to overlie completely, all sizes of collars supported on the form. Such a pad should be of a height substantially equal to the height of the frusto-conical form, so as to iron collars supported at any level thereon.

If it is desired to heat the ironing pad 30 by electric current, it may be desirable to lead the current through a wire extending upwardly from the wire 17 inside of the form to a socket mounted upon the boss 19. The stud 21 should then be in the form of an electric plug having a wiping contact with concentric conductors in the socket. A wire from the plug should then extend either through or around the handle 28 and be connected to the pad by any appropriate arrangement, such as that described above, sufficient slack being left in the wire to permit vertical adjustment of the bar.

The invention is not limited to the structure shown and described, or to the modification suggested above, but includes all devices coming within the scope of the appended claims, or their equivalents.

I claim:

1. A collar pressing machine comprising a collar supporting form and an ironing appliance operatively associated therewith to facilitate ironing of the exterior surfaces of collars on said form, said form comprising a substantially vertically disposed tapering body having a length in excess of its mean diameter and adapted to receive collars of different sizes at different levels in snug fit thereon, said ironing appliance comprising an ironing pad mounted for movement on an axis disposed centrally of the form and around the outer surface thereof, said pad having a concave ironing surface disposable in ironing engagement with collars of all sizes positioned on said form at all different levels thereon.

2. A collar pressing machine comprising a form adapted to serve as a support for a collar to be pressed, said form being of a frusto-conical shape corresponding substantially to the natural taper 5 of a collar, whereby a collar may be applied thereto over the small end and moved toward the large end until a snug fit is secured between the collar and form to shape the collar to its original and natural taper, in combination with an ironing device 10 vice having an ironing face adjustably mounted longitudinally of the surface of said form and adapted to be moved over the surface of a collar positioned on said form, whereby said collar may be shaped and smoothed.
- 15 3. A collar pressing machine comprising a form adapted to serve as a support for a collar to be pressed, said form being of a tapering shape corresponding substantially to the natural taper of a collar, whereby a collar may be applied thereto 20 over the small end and moved toward the large end until a snug fit is secured between the collar and form to shape the collar to its original and natural taper, said form having a longitudinal groove in its outer surface adapted to receive the 25 collar button of collars placed thereon, in combination with an ironing device mounted for movement over the surface of said form and adapted to be moved over the surface of a collar positioned on said form, whereby said collar may 30 be shaped and smoothed.
4. A collar pressing machine comprising a form adapted to serve as a support for a collar to be pressed, said form being of a shape to receive collars of different sizes in snug fit on its exterior 35 surface, in combination with an ironing appliance pivoted to said form and mounted for movement over the exterior surface of the form, said appliance comprising an ironing pad operatively associated with the pivotal connection of said appliance and mounted for ironing movement on a 40 path concentric to the exterior surface of the form on a transverse plane thereof said pad being bodily movable longitudinally of the form to change the position of the pad so as to engage collars positioned at different points on said form.
- 45 5. A collar pressing machine comprising a heated form adapted to serve as a support for a collar to be pressed, said form being of tapering shape and being adapted to receive collars of different sizes in snug fit on its exterior surface, said form having an axially disposed socket in its 50 upper end, in combination with an ironing device pivotally connected to said socket and mounted for rotation on lines concentric to the collar receiving surface of said form, said ironing device having an ironing face mounted for bodily movement longitudinally of the form to change the 55 adjustment of the ironing device for operation upon collars of different sizes positioned on said form at different points.
- 60 6. A collar pressing machine comprising a heated form adapted to serve as a support for a collar to be pressed, said form being of a shape to receive collars of different sizes in snug fit at different positions on its exterior surface, in combination with an ironing appliance pivoted to said form and mounted for movement over the exterior surface of the form, said appliance including an ironing pad mounted for adjustment longitudinally of said form to correspond to the different positions assumed by collars of different size, said pad having an inner face which is concave on a plane at right angles to the axis of said form, said face being adapted to embrace portions of the 65 convex outer surface of collars positioned on said form, to iron the same.
7. A collar pressing machine comprising a heated vertically disposed form adapted to serve as a support for collars to be pressed, said form being of vertically tapering shape, whereby collars of different sizes may be supported thereon at different levels in snug fit, in combination with an ironing appliance including a smoothing pad mounted for movement over the surface of said form along horizontal paths concentric to the surface thereof, said appliance including adjustable means for varying the vertical position of said pad to correspond to the levels at which collars of different sizes are supported on the 70 form.
8. A collar pressing machine comprising a heated vertically disposed form adapted to serve as a support for collars to be pressed, said form being of vertically tapering shape, whereby collars of varying sizes may be supported thereon at different levels in snug fit, in combination with an ironing appliance comprising a member pivotally mounted upon the form, a smoothing pad, and a substantially vertically disposed bar connected at one of its ends to said member and at its other end to said pad, said pad being mounted for movement over the surface of said form along horizontal paths concentric to the surface thereof, the connection at one end of said vertically 75 disposed bar being adjustable, whereby the vertical position of said pad may be varied to correspond to the different levels at which collars of different sizes are supported on said form.
9. A collar pressing machine comprising a heated vertically disposed form adapted to serve as a support for collars to be pressed, said form being of vertically tapering shape, whereby collars of different sizes may be supported thereon at different levels in snug fit, in combination with an ironing appliance comprising a member pivotally mounted upon the upper end of the form, a smoothing pad, and a substantially vertically disposed bar connected at its upper end to said member and adjacent its lower end to said pad, said 80 pad being mounted for movement over the surface of said form along horizontal paths concentric to the surface thereof, the connection at the upper end of said bar, between the bar and the pivoted member being adjustable, whereby the vertical position of said bar and pad may be varied to correspond to the different levels at which collars of different sizes are supported on said form.
10. A collar pressing machine comprising a heated vertically disposed form adapted to serve as a support for collars to be pressed, said form being of vertically tapering shape, whereby collars of varying sizes may be supported thereon at different levels in snug fit, in combination with an ironing appliance mounted for movement over the surface of said form, said ironing appliance comprising a stud disposed on the vertical axis of the form at one end thereof, an arm projecting laterally from the stud beyond the side wall of the form at that end and pivotally mounted for rotation about the axis of said form, a clamp adjacent the outer end of the arm, a bar adjustably mounted in said clamp and extending along the surface of said form, and an ironing pad on the other end of the bar, whereby the bar may be vertically adjusted in said clamp to permit said pad to assume different vertical positions corresponding to the different levels at which collars of different sizes are supported on said form.

11. A collar pressing machine comprising a heated vertically disposed form adapted to serve as a support for collars to be pressed, said form being of vertically tapered shape, whereby collars 5 of varying sizes may be supported thereon at different levels in snug fit, in combination with an ironing appliance mounted for movement over the surface of said form, said ironing appliance comprising a stud disposed on the vertical axis 10 of the form at the upper end thereof, an arm projecting laterally from the stud beyond the side wall of the form at the upper end and pivotally mounted for rotation about the axis of said form, a clamp adjacent the outer end of the arm, a depending bar adjustably mounted on said clamp and extending along the surface of said form, and an ironing pad on the lower end of the bar, whereby the bar may be vertically adjusted in said clamp to permit said pad to assume different 15 vertical positions corresponding to the different levels at which collars of different sizes are supported on said form.
12. A collar pressing machine comprising a form adapted to serve as a support for collars 20 to be pressed, said form being of tapering shape, whereby collars of different sizes may be supported thereon at different positions in snug fit, in combination with an ironing appliance pivoted to said form and mounted for movement over 25 the collar receiving surface of the form, said appliance including an ironing pad mounted for adjustment longitudinally of said tapering form to engage collars supported at different points thereon, said pad having an inner concave face, 30 the arc of concavity of which is no less than the curve of the surface of said form at the largest collar receiving portion, whereby a central section of the concave face of the pad will contact collars of all sizes on said form to permit ironing 35 of said collars.
13. A collar pressing machine comprising a form adapted to serve as a support for a collar to be pressed, said form being of a shape to receive collars of different sizes in snug fit on 40 its exterior surface and being heated by an internal electrical heating element, in combination with an ironing appliance mounted for movement over the collar receiving surface of the form, said appliance comprising an electrically heated 45 ironing pad mounted for adjustment longitudinally of said form to engage collars supported at different positions thereon, said pad being adapted to cooperate with the heated form to permit ironing of collars supported on said form.
14. A collar pressing machine comprising a form adapted to serve as a support for collars to be pressed, said form being of longitudinally tapering shape, whereby collars of different sizes 50 may be supported thereon at different positions in snug fit, in combination with an ironing appliance including a smoothing pad mounted for movement over the surface of said form along paths transverse to the axis of the form and concentric to the surface thereof, said appliance including adjustable means for varying the longitudinal position of said pad on said form to correspond to the different positions at which collars of different sizes are supported on the form, said pad having a longitudinal dimension at least equal to the dimension of a collar at the highest point, whereby the entire surface of a collar may be ironed without changing the adjustment of said pad.
15. A collar pressing machine comprising a heated form adapted to serve as a support for collars to be pressed, said form being of a tapering shape corresponding substantially to the natural taper of a collar, whereby a collar may be applied thereto over the small end and moved 100 toward the large end until a snug fit is secured between the collar and the form to shape the collar to its original and natural taper, in combination with an ironing device removably mounted upon the smaller end of the form and 105 comprising an ironing element mounted for adjustment longitudinally of the tapering form and constructed and arranged for movement over the surface of a collar positioned thereon, the removal of said ironing appliance permitting free 110 application and removal of collars to and from said form without hindrance by the ironing device.
16. An ironing tool for use with a heated collar supporting form, said tool being adapted to iron 115 and smooth the upper rounded edge of a collar supported on said form and comprising an ironing pad having a face which is concave on one axis to correspond substantially to the convex outer surface of a collar supported on said form, 120 said face having a sharply rounded concave portion on a line transverse to said first-mentioned axis, said last-mentioned portion being shaped to impart the desired rounded curve to the upper edge of a collar supported on the form.
